232,300

SCREW DRIVER WITH WIRE STRIPPER

Marvin J. Freed, 8 Leviton St., Tel Aviv, Israel

Filed Sept. 12, 1972, Ser. No. 288,352

Term of patent 14 years

Int. Cl. D8—05

U.S. Cl. D8—87

FIG. 3

FIG. 1

FIG.2

FIG. 1 is a side elevational view of the screw driver with wire stripper showing my design;

FIG. 2 is a front elevational view of the screw driver with wire stripper of FIG. 1; and

FIG. 3 is a top plan view of the screw driver with wire stripper of FIG. 1.

I claim:

The ornamental design for a screw driver with wire stripper, as shown.
